UNITED STATES PATENT OFFICE.

AUSTEN H. FOX, OF NEW YORK, AND ARNOLD W. LENDEROTH, OF STAPLETON, NEW YORK, have invented certain new and useful Improvements in Controlling Devices, of which the following is a full, clear, and exact description.

1,323,261. Specification of Letters Patent. Patented Dec. 2, 1919.

Application filed August 10, 1918. Serial No. 249,300.

To all whom it may concern:

Be it known that we, AUSTEN H. FOX and ARNOLD W. LENDEROTH, both citizens of the United States, residing at, respectively, New York, county and State of New York, and Stapleton, county of Richmond, and State of New York, have invented certain new and useful Improvements in Controlling Devices, of which the following is a full, 10 clear, and exact description.

In a system for railway speed control or other analogous purposes devised by us and now set forth in numerous patents, we employ a track actuated controlling mechanism, 15 contained in a housing or casing which is suspended from the truck of a moving vehicle in close proximity to a rail of the track, and which comprises as its chief and essential elements an electro-magnet with a movable core which is held in a certain position by the attractive effect thereon of a rail of magnetic iron or steel, but which, in passing a break in the magnetic continuity of such rail is shifted to a second position by the 20 then preponderant attractive effect of a fixed magnetic body within the casing.

Our present invention is not directly concerned with the nature of the use of this device nor in general with the character of 25 the system of which it forms a part, but pertains to the construction of the device itself, and consists in improvements thereon, the purpose and nature of which will be understood from the following prefatory consideration.

These devices are designed to be brought 30 into operation by breaks of predetermined lengths in the magnetic continuity of the rails of a track, such breaks being usually produced by the insertion of sections of manganese steel, which is non-magnetic, but we have found in practice that the ordinary 35 tracks, including frogs, switches, turntables, and the like, are likely to contain magnetic breaks which, while not noticeably extensive under ordinary conditions of use, are nevertheless sufficient to operate the controlling device when no such operation of the same is intended or desired. This has rendered it necessary for us to devise a device which 40 will not be influenced by such casual interruptions of the magnetic circuit, but will only yield to such as are designedly made of a length sufficient to produce the desired 45 effect.

In the form of device which we have produced to meet the above requirements we have introduced other features of novelty which contribute to its practical success, and these will be described more in detail hereinafter.

In the accompanying drawings:

Fig. 1 is a view in elevation of our improved device, a part of the inclosing casing being broken away to exhibit the interior mechanism.

Fig. 2 is a longitudinal section of the casing showing the interior parts mainly in elevation.

Fig. 3 is a cross sectional view on line 70 3-3 of Fig. 2 and the rail over which it travels.

Fig. 4 is a section on line 4-4 of Fig. 2, showing a device controlled by the movable magnetic core.

Fig. 5 is a horizontal section on the line 5-5 of Fig. 4.

Fig. 6 is a view in section on line 6-6 of Fig. 2, and

Fig. 7 is a diagram showing circuit connections.

The operative mechanism is contained in a box or casing 1 of the proper shape and dimensions above described, which is designed to be supported from a rigid part 85 such as the equalizer 2 of a car truck immediately back of a car wheel. For practical reasons the ends of the casing have inclined lower corners, as shown, and for like reasons the casing is supported by arms 3 pivoted to 90 arms 4 and resting against stops 5, so that when struck by any object the casing may yield and tilt to a slight extent. The material of the casing is non-magnetic metal, and its bottom is designed to run over the rail with a small but sufficient clearance for all practical purposes.

Within the casing is mounted a horizontal magnetic core 6 (see Fig. 2), having two coils 7-7 thereon, which when supplied 100 with current produce a consequent magnetic pole at the center and two opposite poles at the ends of the core. The central consequent pole is extended by the vertical core portion 8 to the bottom of the casing where 105 the said core is extended in an elongated pole 9.

In close proximity to the ends of the stationary core 6 are two movable cores 10, 10, which extend downwardly with their ends 110

THE INVENTION PERTAINS TO APPARATUS OF THIS NATURE normally in the plane of the pole 9, and these are adapted to turn freely about the central axial line of the core 6. For this purpose spindles 11 are mounted in anti-friction bearings in non-magnetic housings 12, set in the ends of the casing 1, and are secured to the cores 10, so that these latter are free to swing or turn, and as the said cores are in close proximity to the ends of core 6 they prolong the magnetic circuit of such core and constitute a movable portion of such circuit. The two cores are rigidly connected by a cross bar or beam 13 secured to them and balanced in this instance by the bar against gravity.

Under normal conditions the circuit of the magnet coils being closed and the cores energized, the rail beneath the casing forms a path which the magnetic lines from the ends of the movable cores seek to follow in the stationary pole 9, and hence these cores are drawn down toward the rail in their effort to complete the magnetic circuit. Should a break in the magnetic continuity of the rail, however, occur, this directive tendency ceases to a certain extent, whereupon the movable cores are swung up into line with a magnetic body 14 fixed in the casing, which body then exerts a greater attractive effect, owing to its mass and position, upon the movable cores than the fixed pole 9, although such attraction is never greater than that exerted by a rail of magnetic iron or steel.

The above is the general construction of the device, but it is designed with special reference to certain conditions which render its specific details of greater importance. For example, in devices of this class formerly used, a comparatively short and casual break in the magnetic continuity of the rail would bring about an unintended operation of the device, but this instrument is not subject to such objections as it will not be affected by any break, however extended, provided it be not beyond the limits permissible under ordinary railroad practice.

For this purpose the foot or pole piece 9 is made of a greater length than the longest permissible break so that sufficient attractive force will always be exerted on one side at least of a break to prevent the movable core from rising in obedience to the preponderating attraction of the fixed magnetic body 14.

The structure shown, moreover, has other useful properties which are not readily explainable. It will be noted, for example, that for its proper operation it is necessary that the normal line of travel of the ends of the movable parts of the magnetic core should be directly over the top of a rail, and that the pivotal points therefore shall be several inches above and to one side of the line of the rail. It consequently results that

when a section of non-magnetic rail occurs which is not designed to operate the device but used for other structural purposes it would bring about an undesired operation of the device. In such cases, for purpose of our system, it has been usual heretofore to attach to the side of the rail an iron or steel bar, which would act in place of the rail itself to preserve the proper position of the controlling cores or magnets. 75

It is particularly desirable in such cases that this bar should be below the top of the rail, but we have found that with the above described device such bar is not adequate for the purpose, and that the movable cores will rise in passing over it and assume a position in line with the fixed magnetic body 14. This, however, we have found may be entirely overcome by magnetizing the inserted bar, as by means of cores 85 and coils secured thereto. This is shown in Fig. 3, where 15 designates bars of iron or soft steel preferably attached to each side of the web of the rail 16 and magnetized by electro-magnets 17, the cores of 90 which are secured to said bars. The magnets may be placed at intervals over any length of bar and are designed to impart to both bars magnetism of the same sign, but opposite to that of the movable cores 95. 10. This entirely obviates the tendency of the cores to move upward when passing over a section of non-magnetic rail.

It is not desirable that the movable cores should be free to swing beyond the perpendicular in the direction of their downward travel, and for this purpose fixed stops have heretofore been employed to limit their movement. But it has been found that owing to the shocks and jars to which the devices are constantly subjected such means are not adequate, and that the cores are liable to jump or rebound beyond the proper limits. To avoid this—and the means adopted for the purpose has been found to be 100 most effective—we attach a flexible strap to a stationary part of the device and carry it over the rotating part of the movable core and attach it to the latter. This is shown in Fig. 6, in which 18 is a steel tape 115 secured at one end to the housing 12 and at the other to any part of the spindle 11 after passing over its top. By the use of this expedient the movement of the core may be limited in either or both directions, as may 120 be desired, as is manifest from the function ascribed to the single tape shown.

To indicate the nature of the use of this device we have shown in Figs. 4 and 7 a circuit controller 20 operated by the movable cores. The details of this may be very greatly varied, but as shown, when the movable cores are in normal or rail attracted position the conducting portion 21 of the circuit controller engages with a contact 130

which completes a circuit through an electric lamp 22. Should the cores rise, this contact is broken and the lamp extinguished.

It is obvious that circuits may be opened or closed prior to either of the limits of motion of cores 10. ~~10. H. C. G. 10.~~

The details of the construction of this device may obviously be greatly varied in many particulars, but what we claim is:

1. In a device of the kind herein set forth, the combination of a casing having a horizontal portion with a dependent portion at one end which portion is not wider than a car wheel, means for supporting the casing from a car truck immediately behind a car wheel, a fixed magnetic core and movable magnetic core contained in the casing, the movable cores extending through the dependent portion with their ends adapted to swing into close proximity to the rail.

2. In a device of the kind herein set forth, the combination with a casing adapted to be suspended from a moving vehicle in close proximity to the rail, of a fixed or stationary magnetic core, coils thereon that produce a consequent magnetic pole at its center, a downward extension of such consequent pole, two movable poles swinging about the central axis of the stationary core and a magnetic body which in the absence of a magnetic rail beneath the device attracts and raises the movable cores.

3. In a device of the kind described the combination with a casing adapted to be suspended from a moving vehicle in close proximity to a rail, of a magnetic system therein comprising a horizontal magnetic core with a central prolongation toward the rail provided with an elongated pole piece, coils which produce a consequent magnetic pole at the center of the core, and movable cores pivoted in the line of the axis of the horizontal core so that their ends may swing into line with the central pole piece, and a magnetic body within the casing which, in the absence of a magnetic rail under the device, attracts and raises the movable cores.

4. In a device of the kind described, the combination with a casing adapted to be suspended from a moving vehicle in close proximity to a rail, of a magnetic controlling device therein comprising a magnetic core having a fixed and a swinging portion, of a tension band encircling more or less the shaft of the swing portion, having one end secured to the casing and the other to said shaft for limiting the movement of the same in one direction.

5. In a device of the kind described, the combination with a casing adapted to be suspended from a moving vehicle in close proximity to a rail of a magnetic controlling device therein comprising a fixed cen-

tral pole and two swinging poles of opposite polarity to the central pole, and adapted to be held in line with the central pole while passing over a magnetic rail, and means for raising the movable poles when the attractive effect of a rail ceases.

6. In a device of the kind described, the combination with a casing adapted to be suspended from a moving vehicle in proximity to a rail, of a controlling device within the casing comprising a central fixed pole and two swinging movable poles adapted to be held in line with the central pole by the attractive effect of a rail, the central pole being of such length that short or casual breaks in the magnetic continuity of the rail will not affect the magnetic attraction for the swinging poles.

7. In a device of the kind described, comprising a horizontal core with two coils which produce a consequent pole at its center, and a depending central part of said core having an extended pole piece, of swinging cores pivoted in bearings mounted at the ends of the fixed core, and a magnetic body mounted to one side of the normal position of the swinging cores for the purpose set forth.

8. The device herein described, comprising a horizontal fixed core with a right angled extension from its center having an elongated pole piece, coils which produce a consequent pole in said pole piece, spindles in bearings supported at the ends of the fixed cores, swinging cores secured to said spindles and cooperating with the central stationary pole, and means for attracting and raising said movable cores when not attracted by a rail over which the device may be passing.

9. The means herein described, for limiting the movement of swinging cores, comprising spindles mounted in bearings at the ends of the fixed core and carrying movable cores, tension bands secured at one end to a fixed support and carried around the spindles and secured at the other end thereto.

10. The magnetic system for controlling devices herein shown and described, comprising a horizontal core, a central depending core with an elongated pole piece, coils which produce in said pole piece a consequent magnetic pole, movable cores pivoted at the ends of the horizontal core and adapted to swing about the central axis of the same, and a magnetic body of greater mass than the pole piece, fixed in position to attract and raise the ends of the movable poles when other and stronger attractive influences thereon are not present.

11. In a system of the kind described, in combination, a controlling device supported from a moving vehicle in close proximity to a rail, and comprising opposite magnetic

- poles attracted toward each other by the tendency of the magnetic lines to bridge the gap between said poles through a magnetic rail, and a rail having casual breaks in its magnetic continuity, one of the said opposite magnetic poles being of such length as to bridge the casual breaks and thus insure the

operation of the device notwithstanding the occurrence of such breaks.

In testimony whereof we affix our signatures. 10

AUSTEN H. FOX.

ARNOLD W. LENDEROTH.
